CLOCK

Filed March 19, 1932

John O Simpson
Sagamore Earle & Nichols
Attnys.

UNITED STATES PATENT OFFICE

JOHN O. SIMPSON, OF BRISTOL, CONNECTICUT, ASSIGNOR TO THE E. INGRAHAM COMPANY, OF BRISTOL, CONNECTICUT, A CORPORATION

CLOCK

Application filed March 19, 1932. Serial No. 599,880.

This invention relates to an improvement in clocks, and relates in particular to the supporting feature thereof.

Heretofore, it has been the general practice when it was desired to provide clocks with a plurality of small distinct feet, to apply the same individually to the case of the clock. This practice involved extra cost, both as to manufacturing and assembly, and also resulted in a structure lacking the requisite strength and stability to withstand hard usage. The employment of individual feet also rendered more difficult the problem of applying various finishes, such as lacquer, etc.

The main object of my present invention is to provide at a low cost for manufacture a clock having attractive and rugged supporting-means characterized by ease and convenience of assembly.

A further object of my invention is to provide a clock having unitary supporting-means which will effectively simulate a plurality of individual feet, and at the same time possess strength and permanence to a degree superior thereto.

With the above and other objects in view, as will appear from the following, my invention consists in the combination with a clock-case, of a sheet-metal foot-plate having formed therein a plurality of integral, hollow, boss-like projections, and secured to the said clock-case in position to cause the latter to conceal the hollow interior of the said integral, hollow, boss-like projections.

My invention further consists in a clock characterized as above and having certain features of construction and combinations and arrangements of parts as will be hereinafter described and particularly recited in the claims.

In the accompanying drawing:

Fig. 1 is a face view of one form which a clock embodying my invention may assume;

Fig. 2 is a view thereof in side elevation;

Fig. 3 is an under-side view thereof;

Fig. 4 is a broken view in transverse section, taken on the line 4—4 of Fig. 1;

Fig. 5 is a broken longitudinal sectional view taken on the line 5—5 of Fig. 2;

Fig. 6 is a horizontal sectional view taken on the line 6—6 of Fig. 1; and

Fig. 7 is a perspective view of the foot-plate, detached, and looking toward the under-face thereof.

The particular clock herein chosen for the illustration of my invention includes a rectangular cup-shaped sheet-metal case 10 having an integral back 11 and having its otherwise open front closed by a bezel 12, mounting the usual dial 13 and convex crystal 14, through which latter the said dial is visible as well as the hour- and minute-hands 15 and 16 respectively of the clock.

The bottom-wall 17 of the rectangular case 10 is provided with two upstanding spaced-apart bushings 18—18, each having a threaded bore 19 and secured to the said bottom-wall 17 by riveting, as at 20. The said bushings 18—18 are respectively located 70 adjacent the respective opposite sides of the case, as shown in Fig. 5, in position to respectively receive one of two fastening-screws 21—21 extending upward through suitable perforations 22 formed in a sheet-metal foot-plate 23 and serving to hold the said plate against the under-face of the said bottom-wall 17 of the case 10.

At each of its four corners, the foot-plate 23 is downwardly struck to form a hollow 80 boss-like projection or foot 24, which may be of any approved form such, for instance, as the inverted pyramidal form shown.

With the foot-plate 23 secured in place to the under surface of the bottom-wall 17 of 85 the case 10, it not only serves to stiffen and reinforce the same, but the hollow character of the boss-like projections or feet 24 is concealed and to the eye a true simulation of a plurality of individual feet is presented.

The hollow projections or feet 24, however, as thus made integral with the plate 23, are definitely spaced and positioned with reference to each other and possess far more ruggedness than a similar number of separate and distinct feet individually secured to the case and relying alone thereon for anchorage. Moreover, the weight of the entire unit, including the plate 23 and its bosses 90

24, need not exceed the weight of as many individually-formed solid feet.

- 5 Furthermore, in the event that it is desired to color or tone the feet a different shade from the body of the case, the case itself may be lacquered or otherwise finished in appropriate color, and the foot-plate 23 similarly treated and later secured in place to the said case 10 with ease and facility.
- 10 If extreme lightness is desired, the foot-plate 23 may be skeletonized by, for instance, cutting out the metal enclosed within the dotted lines 25, shown in Fig. 7.

15 It will be understood by those skilled in the art that my invention may assume varied physical forms without departing from my inventive concept and I, therefore, do not limit myself to the specific embodiment herein chosen for illustration, but only as

20 indicated in the appended claims.

I claim:

- 25 1. The combination with a clock-case; of a sheet-metal foot-plate having struck downwardly therefrom a plurality of integral hollow boss-like feet and secured to the under-face of the said clock-case in position to cause the same to conceal the upper face of the said plate and the hollow interiors of the said integral boss-like feet.
- 30 2. The combination with a clock-case; of a substantially-rectangular sheet-metal foot-plate having struck downwardly from each of its corners an integral hollow boss-like foot and secured to the under-face of the said clock-case in position to cause the same to conceal its upper face and the hollow interiors of the said integral boss-like feet.
- 35 3. The combination with a clock-case; of a sheet-metal foot-plate having formed therein a plurality of downwardly-tapering hollow boss-like feet and secured to the under-face of the said clock-case in position to cause the same to conceal its upper face and the hollow interiors of the said downwardly-tapering boss-like feet.

45 In testimony whereof, I have signed this specification.

JOHN O. SIMPSON.
